CLOSURES FOR PAPERBOARD CONTAINERS

Walter C. George and Clifford D. Fallert, St. Louis, Mo., assignors, by mesne assignments, to Crown Zellerbach Corporation, San Francisco, Calif., a corporation of Nevada

Application December 6, 1954, Serial No. 473,150

4 Claims. (Cl. 229—45)

This invention relates to an improvement in the closure seal between the cover panel and body member of polygonal containers of the class generally referred to as Drumpaks, specific examples of which are disclosed and illustrated in United States Letters Patent Nos. 2,214,220 and 2,620,119. The closing means for containers of the class described comprises a separate cover member substantially conforming in shape to a horizontal cross-section of the erected body member and having locking flaps on each side edge. The cover member is attached to the body member by folding the locking flaps downwardly and inwardly into interengaging and/or interlocking relation with matching locking flaps on the ends of the wall panels of the body member and maintaining the flaps in the closed interlocked position parallel to the body wall panels by attaching an encircling band thereabout. The interlocking flap closure system provides a seal under continuing tension between the flap folds at the ends of the body member panels and the underface of the cover member.

The present invention contemplates providing a Drumpak or polygonal container having closure means, as described, with an inner liner and with relatively rigid pads, conforming in shape to the horizontal cross-section of the body member of the Drumpak container, for closing the open ends of the liner. The liner is shorter than the body member panels by about twice the thickness of the board so that the upper faces of the closure pads, when in place, will be substantially in the plane of the end edges of the body panels and in flatwise contact with the underface of the Drumpak closure member in the closed position thereof. A sheet of highly resilient cushioning material of the same general shape as the closure pads, but of larger diameter, may be secured to the inner face of the pad. When the pad with the cushioning material is placed over the open end of the liner and the body flaps are in their initial outwardly extending position, a portion of the cushioning material will overlap an inner portion of the body locking flaps. Thus, when the closure member is secured to the body member, the resilient cushioning material will be interposed and compressed over several areas, namely, between the end edges of the liner and the side edges of the pad, between the side edges of the pad and the upper margin of the body panels, between the fold at the upper end of the body panel and the underface of the closure member and also between the interengaged or interlocked body and closure flaps. The several compressed areas of the cushioning material serve to distribute the force of any sharp impact incident to handling and transportation over a much greater area of the container structure and thus protect the integrity of the closure structure and provide a permanent tension seal which is proof against siftng of materials not only in pellet and granular form, but of fractional micron particle size, such as impalable powder.

Highly resilient materials especially suitable for the purpose of the invention are wood cellulose fibers, par-

2

tially or well purified, bonded or felted into sheets or rolls formed of about $\frac{1}{8}$ to $\frac{1}{4}$ inch thickness in their normal uncompressed state. The cellulosic material may comprise a plurality of tissue-thin sheets bonded or laminated into fluffy, compressible, highly resilient wadding or cushioning material. The sheets and rolls may be provided with a backing of kraft paper to facilitate fastening the material to surfaces if desired. Examples of the described cellulosic material suitable for the purpose of the invention are laminated, creped cellulose fiber wadding or cushioning materials known in the trade as "Kimpak" and cellulose fiber padding known as "Tufflex." However, any other highly resilient material of suitable thickness may be interposed between the elements of the Drumpak container for the purposes hereinbefore described.

An object of the invention is to provide an improved sift-proof seal for the ends of polygonal containers of the kind generally referred to as Drumpaks by interposing a sheet of highly resilient cushioning material between the closure panel and the upper end edge of the body member and between the interlocked closure and body flaps of the Drumpak.

Another object is to provide a polygonal container or Drumpak with an inner open ended liner and a closure pad of substantially the same shape as the horizontal cross-section of the body member, positioned over the free end edges of the liner and in contact with the underface of the closure member, and an interposed sheet of highly resilient cushioning material between the closure pad and the upper end edges of the liner and also between the upper end edges of the container body and the underface of the closure member and extending between the interlocked closure flaps, forming an effective barrier to the passage of finely divided material, even impalable powdery substances.

These and other objects will be apparent to those skilled in the art upon a full and complete understanding of the construction and operation of the invention.

The invention also consists in the parts, arrangements and combinations of the parts hereinafter described.

The accompanying drawings form a part of this specification and like numerals and symbols therein appearing refer to like parts wherever they occur.

Fig. 1 is a plan view of the top of a polygonal Drumpak container with portions of the closure member and the closure pad cut away to show a portion of the wall structure and the cushioning material;

Fig. 2 is a front elevation of the Drumpak container with the closure members attached and secured in closed position by encircling bands;

Fig. 3 is a vertical, sectional view of the container of Fig. 2 taken in the direction of the arrows 3—3;

Fig. 4 is a vertical, sectional view of the container showing the cover member in an intermediate stage of closing;

Fig. 5 is a vertical cross-sectional view of the upper portion of the container of Fig. 2 taken in the direction of the arrows 5—5;

Fig. 6 is an exploded perspective view of the several elements of the top and bottom closures of the container positioned in the order in which they are combined with the body section;

Fig. 7 is an enlarged plan view of a corner of the container shown in Fig. 2; and

Fig. 8 is an enlarged perspective view of a corner and the adjacent walls of the container adjacent the interlocking closure flaps.

A fully erected octagonal Drumpak container of a preferred form of interlocking closure means with the top and bottom closures attached is shown at A in Fig. 2. The container comprises an octagonal body section B,

Fig. 6, with top and bottom closure flaps 10, integral with body panels 11 and foldable about the scores 12. The cover member C consists of a cover panel 13 similar in shape to a horizontal cross-section of the body member B. Each side edge 14 of the cover panel has an integral closure flange 15 with notches 16 for receiving an encircling band 17, Fig. 2, in the closed position of the cover member. Each of the flanges 15 has a locking flap extension 18 which is rebent about score 19 which becomes interlocked with the body flap 10 in the closed position of the cover member. The body member B has an interior, open-ended liner 20 snugly fitting the interior thereof with its end edges 21 terminating a slight distance inside the ends of the body panels 11. A closure pad 22 corresponding in shape to a horizontal cross-section of the interior of the body member B, with side edges 23 corresponding to the width of the body panels 11 is adapted to fit snugly inside the body member B over the ends 21 of the liner 20. A sheet of highly resilient cushioning material 24, which may be of the same outline as the closure panel 13, and the closure disk 22, which is somewhat larger in diameter than either and has side edges 25, is adapted to extend over the body flaps 10 where they are extended outwards from the body member B.

The closure member C may be attached to the body member B by first folding the body flaps 10 outwardly. The sheet of cushioning material 24 may be attached to the underside of the closure pad 22 in any convenient way, for example, by glue or other suitable means with the edges 25 of the cushioning material in parallel alignment with the edges 23 of the closure pad. The cushioning material and closure pad are then placed over the outwardly folded body flaps 10 with the side edges 23 of the closure pad in vertical alignment with the end edges 21 of the inner liner 20 of the body member B. The side edges 25 of the cushioning material will now extend over a substantial portion of the body flaps 10. The cover member C is next placed over the closure pad 22 with the sides 14 of the cover panel in substantially vertical alignment with the side edges 23 of the closure pad and the outer face of the body panels 11. The flanges 15 of the cover member are then folded downwardly and the closure flaps 18 rebent about the score 19 and interposed between the body panel 11 and the body flaps 10. The downward movement of the flanges 15 is continued until they are in substantially parallel relation to the body panels 11 with the rebent flaps 18 in flatwise relation to the panels 11 as shown most clearly in Fig. 5.

In this closed position, the cushioning sheet 24 will be compressed over the top edge 21 of the liner and in compressed, abutting relation to the inner face of the body panels 11. It will also be compressed between the sides 23 of the pad 22 and the upper margin of the body panel 11. Another compressed area of the sheet is between the underface of the cover panel 13 and the fold 26 of the body flaps over the end of the body panel and it will also be tightly held between the interlocked body flaps 10 and the closure flanges 15 by the encircling band 17 which is held in place by the notches 16.

As the closure flanges 15 are forced downward into parallelism with the body panels 11 and the rebent locking flaps 18 interposed between the body flaps 10 and the wall panels 11, an increasing tension between the several adjacent parts of the body member B and the cover member C gradually compresses the interposed cushioning material to a relatively high degree over the several relatively wide areas, as illustrated in Fig. 5, and this compression of the cushioning material is maintained continuously as long as the encircling band 17 is in place around the flanges 15. These compressed portions of the cushioning material form a very effective dam or seal to the passage of very finely divided material, for example, particles of fractional micron size, either from within the container outwardly or vice versa. The highly re-

silent pad of cushioning material between the elements of the body member and the closure member serve a further important feature of distributing the force of the sharp impacts incident to handling and transportation 5 and to minimize or substantially eliminate the possibility of such impacts impairing any portion of the tension seal provided by the invention.

The hereinbefore described method of interlocking the cover and the body flaps of the Drumpak container is a preferred system but similar results may be obtained by folding cooperating pairs of flaps into parallelism with the body panels in modified relation to each other. For example, by adjusting the lengths of the cover flaps 18 and the body flaps 10 so that their free ends will be in 15 abutting relation under tension in the closed position of the Drumpak container cover. Variations of suitable flap interengaging methods are described in the United States patents hereinbefore mentioned.

The particular embodiment described and the variations thereof are intended to be illustrative and not restrictive, and it is to be understood that the invention herein is applicable to further modified forms of Drumpak containers and all such modifications which are similar or equivalent thereto come equally within the claims next 20 appearing.

What we claim is:

1. A sift-proof closure means for a polygonal container comprising a body member formed of a plurality of connected together wall panels each having outer marginal flaps, an inner liner slightly less in length than the body wall panels, a closure pad corresponding in shape to a horizontal cross section of the interior of the body member adapted to snugly fit inside the end margins of the body member and seat on the free end edges of the inner liner, and a cover panel corresponding in shape to a cross section of said body member secured to the end of said body member by integral flanges on each side edge of said cover panel with locking flaps on their outer edges interengaged or interlocked with matching flaps on the ends of the body panels; said sift-proof closure means comprising a sheet of resilient cushioning material of greater diameter than said closure pad positioned on the underface of said closure pad and interposed and compressed between the upper free edges of said inner liner and the under face of the side margins of said closure pad, between the upper margin of said body panels and the side edges of the said closure pad and between the fold of the closure flap at the upper edge of said body panel and the underface of said cover member.

2. The combination set forth and claimed in claim 1 wherein said cushioning material extends beyond the sides of the cover panel into interposed relation between the interlocked cover flanges and body flaps.

3. The combination set forth and claimed in claim 2 wherein peripheral portions of said cushioning material are also compressed between said interlocked cover flanges and body flaps.

4. A closure means for a polygonal container impermeable to solids of fractional micron size, said container comprising a plurality of connected together wall panels forming an open ended body member, each of said panels having an integral end margin locking flap, an inner liner slightly less in length than the body wall panels for said body member with a rigid closure pad conforming in shape to the inner periphery of said body member positioned over said liner with its side edges adjacent the end margins of the body panels and in vertical alignment with the ends of said liner, and a cover member with side edges corresponding in number to the body member panels, said cover member being secured to the end of each body member by integral marginal flanges on each side edge thereof with locking flaps on their outer edges interengaged or interlocked with said body member flaps, said impermeable closure comprising a pad of highly resilient cushioning material of greater diameter than said

liner closure pad, said cushioning pad being secured to the underface of said closure pad and compressed between the interengaged body flaps and the cover member flanges, between the upper end of the body walls and the underface of the closure member, between the upper end edges of said liner and the underface of said liner closure pad and also between the outer edges of said liner closure pad and the end margin of said body panel.
